TELEPHOTO SYSTEM

Frank J. Somers, San Jose, Calif., assignor, by
mesne assignments, to Farnsworth Television &
Radio Corporation, Dover, Del., a corporation
of Delaware

Application March 27, 1935, Serial No. 13,253

9 Claims. (CL. 178—6.7)

My invention relates to a system for transmission of visual information at a distance and relates more particularly to a system designed to transmit and receive images having several gradations of light value.

Among the objects of my invention are: To provide a telephoto system wherein transmission is satisfactory over a circuit or channel where the signal-to-noise ratio may be as low as 2 or 3-1; to provide a system adapted for the transmission and reception of photographs, drawings or the like, in so-called half-tone form; to provide a system adapted for the transmission of photographs having various degrees of light and shade; to provide a telephoto system having minimum inertia limitations; to provide a telephoto system whereby enlargement or reduction may be made in the size of the reproduced image from that of the original picture field; to provide a system for the transmission of photographs or other half-tone reproductions to a distant point, utilizing the lower grades of commercial channels, either wire or radio; to provide a system of telephoto transmission having a minimum interference factor; to provide a telephoto system capable of operating at high speed; to provide a telephoto system utilizing certain desirable characteristics of a grid-controlled arc-rectifier; to provide a telephoto system wherein amplitude changes during transmission have a minimum effect upon the received image; to provide a telephoto-receiving system giving a record in permanent form and a visual image simultaneously; to provide a telephoto-receiving system wherein photographs or other half-tones can be made available at least in part immediately upon reception and be preserved in recorded total form thereafter; to provide a telephoto system utilizing desirable characteristics of cathode ray tubes; to provide a simple and efficient means and method of transmitting telephoto images over wire or radio channels; to provide a telephoto system wherein the transmitted impulses are all of equal amplitude irrespective of the degree of light and shade they represent; to provide a telephoto system which can be operated over channels hitherto adapted only for facsimile transmission; to provide a means and method for selecting impulses of uniform amplitude from a heterogeneous train of impulses having varying magnitudes; to provide a means and method of transmitting half-tone picture fields, which includes direct scansion of three dimensional subjects and reproducing said images and/or subjects in the form of a multi-tone photographic record and as a visual picture

simultaneously; and to provide a preferred telephoto system utilizing at least in part certain desirable characteristics of any or all of the inventions disclosed and claimed in the following patents and applications:

and others.

Certain features herein disclosed are more fully described and claimed in my co-pending application, Serial No. 13,252, filed March 27, 1935, for a facsimile system, the preferred embodiment of the present invention utilizing some features in common with the preferred embodiment shown therein.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

Referring to the drawings:

Figures 1 and 2, when combined, form a diagrammatic circuit reduced to lowest terms of a preferred form of telephoto transmitter employing my invention. In order that the diagram may be conveniently followed in the break between the two figures, circuit connections common to the two figures are lettered on each figure with corresponding characters from A to K, inclusive.

Figure 3 is a diagram representing a preferred waveform for rectifier anode supply.

Figure 4 is a circuit diagram reduced to lowest terms of a preferred telephoto receiver.

Figures 5 and 6 are diagrams representing the characteristic curves of the grid-controlled arc rectifiers, showing preferred steady biasing values.

Figure 7 is a diagram showing the preferred varying bias values of the arc-controlled rectifier.

In comparing telephoto transmission with facsimile transmission, it will be found that telephoto is, in a number of respects, more complicated in the equipment required. Defining the terms as herein used, telephoto transmission comprises the transmission of an original picture field and the reproduction of that field preferably and usually at a distant receiving station in all or at least part of its intermediate shades or half-tones. On the other hand, facsimile transmission does not attempt to transmit partial values, but merely transmits the extreme contrasts of black and white. Telephoto, therefore, adds to the problem of facsimile the necessity of transmitting relatively fine variations of amplitude due to closely adjacent shades in the original picture field, in addition to the extreme contrasts of black and white. The usual systems of telephoto heretofore disclosed attempt to scan a picture field with an aperture, the number of shades transmitted between complete black and complete white being regulated by controlling the size of the aperture. It has usually been thought desirable to make the aperture as small as possible, thereby securing a large number of value levels between the extremes of light and dark. This procedure leads to a signal train of extremely high frequency, and consequently, if modulated on a radio carrier, leads to wide side bands, and the necessity for wide channels; and if sent over a wire line requires special phase correction and other corrections well known in the art to prepare the line for the transmission of a wide frequency band.

Furthermore, such prior telephoto transmission is based upon amplitude relations and the channels not only require correction, but also require a signal-to-noise ratio of at least 20-1 for satisfactory transmission. My instant invention, however, provides satisfactory telephoto transmission on a radio circuit or other channels where the signal-to-noise ratio is as low as 2 or 3-1, and also utilizes signals of uniform amplitude. Consequently, a less expensive channel can be used, as signals for telephoto transmission can be in the form of interrupted and successive uniform amplitude impulses, thus obviating the necessity of amplitude modulation. No substantial phase or frequency corrections are necessary, providing the radio circuits and equipment are designed with ordinary care according to practices well known in the art.

I have found that there are certain desirable characteristics inherent in the Farnsworth system of electronic scanning, as exemplified, described and claimed in the foregoing list of patents and applications, which, when combined and adapted for my new purpose will produce a preferred system which is ideal for the transmission of telephoto images. It should be fully understood, however, that I do not wish in any way to be limited to the use of the particular apparatus described by Farnsworth and others listed, and it is also to be understood that the actual apparatus used is subject to design variations according to conditions to be met for any particular installations.

In order, however, that the broader aspects of my invention may be understood, which can, as will be apparent to those in the art, be attained by the use of other apparatus, I shall describe herein a preferred embodiment of apparatus to illustrate my invention comprising a complete system for the transmission of telephoto images.

Broadly described, the circuit shown in Figures 1 and 2 is designed to provide for the transmission of half-tone or variable shade pictures without the necessity of resorting to the usual method of continuously varying the amplitude of the carrier in accordance with the varying lights and shades appearing in the picture.

In my present system, it is only necessary to key the transmitter so that all the impulses except those used for synchronizing are of the same shape, amplitude and duration. The pulses which are sent out may be square-topped or rounded, it merely being required that they be uniform.

This method of transmission is obtained by scanning the picture in such a way that the final signal impulses are all of the same length and duration but are sent on a time-distribution basis according to (a) the light intensity of the individual elements which go to make up the picture, and (b), their respective positions on the picture. In this respect, it should be understood that the word "picture" as herein used to describe the picture field to be transmitted, may be either a two-dimensional photograph or similar image, or it may be a three-dimensional subject, producing a two-dimensional optical image on a scanning means.

In practice, the signal train may be obtained by a modification of the ordinary method of scanning a picture a line at a time. In the modification, each line is scanned several times before going to the next, and on each scanning of the same line, the transmitter sends out pulses representing picture elements of one range of light intensities only. Thus, if each line is scanned five times, five different shades, ranging from black to white, will appear in the picture.

In order that the telephoto system herein to be described be restrained to comparative simplicity of circuit, it will be described as having each line scanned five times although it is perfectly obvious that a greater or lesser number of scannings is possible without departing in any way from the spirit of my invention.

While it is true that the picture is in effect scanned several times for one transmission, when this method is used, the number of picture elements transmitted during the scanning is not greater than that which would be obtained in the ordinary scanning method where variable modulation is used, and the same tone gradation is used.

The two main advantages of the system to be described are:

1. The equipment can be made to operate in cases where the signal-to-noise ratio at the receiver is only 3-1 or less compared to a ratio of 20-1 required for variable amplitude transmission;

2. An ordinary radio transmitter such as is used for code messages can be used as it is only necessary to key the carrier on and off in order to transmit a half-tone picture. The power supply for the transmitter should have good regulation so that no objectionable keying transients are introduced, but this requirement has already been met in any well designed radio telegraph transmitter. It should be pointed out that as

far as transmission is concerned, a wire channel adapted to carry the keying frequency is perfectly satisfactory, and the full equivalent of a radio channel.

5 In describing a preferred form of transmitter adapted for telephoto transmission over a radio telegraph channel, I shall refer to Figures 1 and 2, the two figures when combined, forming the complete circuit. The circuit has been divided 10 at the bottom of Figure 1 and continued at the top of Figure 2. The letters A to K inclusive indicate continuations of the same circuit connection. In explaining my transmitter hereafter, the circuit will be described as if it were 15 joined into one complete diagram without further reference to the lettered breaks.

A picture field 1 represented in this case as being a photograph or similar field, but which may be any image or scene which is desired to 20 be transmitted, is focused through a lens 2 on a photoelectric cathode 3 of a dissector tube 4. This dissector tube may be made in accordance with the teaching of the Farnsworth Patent No. 1,773,980, listed above, or may be the improvement thereon as shown, described and claimed in the Rutherford patent above. It comprises an envelope containing the cathode 3 at one end upon which an optical image may be projected by the lens 2. As the cathode 3 is photosensitive, electrons are emitted from the surface thereof in proportion to the intensity of the light striking the elementary areas thereof. A positive potential is applied from a dissector source 25 5 between cathode 3 and a target finger 7 placed close to the opposite end of the tube.

This target finger 7 is in the light path, but being of relatively small diameter and out of the focus of the optical system, it does not cause distortion but merely cuts down the total amount 40 of light reaching the cathode by a small amount. Electrons emitted by cathode 3, therefore, are attracted by the positive potential towards the target finger 7 and are kept in parallel arrangement by the application to the tube of a longitudinal 45 magnetic field created by a focusing coil 8 energized by a focusing source 9 under the control of a variable focusing resistor 10. The target finger 7 is provided with an aperture opening toward the cathode 3 through which electrons emitted from the cathode may pass to be collected by a target represented by a dotted line inside of the finger 7 and being a continuation 50 of the target lead 11.

If the electrons in space are not diverted from 55 their paths in the tube only electrons from a single elementary area of the cathode 3 will arrive on the inner target, the remainder of the electrons being collected by the outer target finger 7. Thus, there will be a difference in the 60 number of electrons collected by the inner target and the outer finger, which will cause a current to flow through an output resistor 12 from target source 6. If the electron beam is then deflected in two dimensions, the electron 65 beam will be scanned and will produce a train of picture signals in output leads 13, which will represent electrically the picture field 1.

Horizontal scanning is accomplished by the 70 use of a horizontal scanning coil 14 which is energized from a scanning oscillator assembly 75 through a scanning secondary winding 15 applied to a core 16 of a transformer having a grid primary winding 17 and a primary plate winding 18 attached to the respective grid and plate circuits of an oscillator tube 19. The constants of

the circuits attached to the oscillator tube 19 are so adjusted that tube 19 will self-oscillate, and also to supply a sawtooth current to the secondary coil 15, consequently, to the horizontal scanning coil 14.

In order to completely scan the picture, it will be necessary to scan the picture vertically as well. A vertical scanning coil 20 is therefore provided energized through leads 21 from a vertical scanning source 22 which is in series with 10 a variable resistor assembly 23 indicated as enclosed by the dotted line 23 in Figure 2. This variable resistor assembly, which may be called a progressive selector, controls the amount of current flowing through the vertical scanning 15 coil 20 in decreasing equal increments.

The action of both the horizontal and vertical scanning is under the control of a synchronizing assembly driven by a synchronous motor 24 which drives a synchronizing rotor shaft 25 20 through reduction gears 26. The synchronizing shaft 25 carries thereon a four-cycle rotor 27 and a twenty-cycle rotor 28. The twenty-cycle rotor is provided with a twenty-cycle field 29 which is connected through leads 25 30 to a control primary 30' on core 16 so that the scanning oscillator 19 is kept in step with the twenty-cycle frequency generated by the twenty-cycle rotor 28.

At the same time a four-cycle field 31 generates 30 a pulse which is fed to the input of a low frequency pulse amplifier tube 32, the output of which passes through a low frequency pulse relay coil 33, the magnetic pull of which acts upon a low frequency pulse armature 34 to place upon a 35 first selector operating magnet 35, current from a selector battery 36. Each impulse applied to the operating magnet 35 causes rotation of first selector shaft 36' by one notch; thus changing the total resistance of combined selector resistors 40 37, 38 and 39. At each revolution of the first selector shaft 36', contacts are made between first selector arm 40 and associated stationary contact 41 which directs a pulse from second selector battery 42 to second selector magnet 45 43, thus turning second selector axle 44 one notch. The process is repeated to control the turning of the third selector axle or shaft 45 in a similar manner. Thus, the entire range of resistance in resistors 37-38-39 may be covered in 50 successive steps and the number of steps provided in the assembly will of course correspond to the number of lines desired in scanning the picture from top to bottom.

It will be seen, however, that as the horizontal 55 scanning is twenty cycles; and the vertical scanning is on a four-cycle basis, that each line will be scanned five times before moving on to the next line. This process repeats itself automatically so that at the end of each group of five 60 sawtooth waves generated by the horizontal scanning oscillator 19, the selectors operate to move the electron beam to present the next line to be scanned to the target aperture of the dissector tube.

The picture currents produced by this scanning process are passed through output resistor 12, and are then fed throughout output lead 13 to a two-stage d.-c. amplifier 46. The output of this d.-c. amplifier is applied to the parallel 70 inputs of two amplifiers, one of them a one-stage amplifier 47 and the other a two-stage amplifier 48. The outputs of these two amplifiers are fed to a pair of grid-controlled arc rectifier tubes, such as are known in the trade under the name 75

"Thyratron," herein called rectifiers for convenience. A rectifier 49 is connected to the output of the one-stage amplifier 47 through a volume control 50, and the output of the two-stage amplifier 48 is connected to rectifier 51 through a similar volume control 52. As the amplifiers 47 and 48 have a different number of stages, it will be seen that the outputs of the two amplifiers are out of phase, the output of the one-stage amplifier 47 being applied to the grid 54 of the rectifier 49 in one direction and that of the two-stage amplifier 48 applied to the grid 55 of the second rectifier 51 in the opposite direction.

15 Rectifier 49, which receives the impulses from the amplifier having an odd number of stages is supplied with a positive steady bias by bias assembly 56, and rectifier 51 which receives its impulses from the amplifier having an even number of stages is supplied with a negative steady bias by negative bias assembly 57.

20 The plates of the two rectifiers are energized by a two thousand-cycle rotor 58 attached directly to the shaft of the synchronous motor 24, 25 this rotor creating two thousand cycle pulses in the main rectifier anode line 59, which passes through a common anode resistor 60 and then divides at a connection 61 and is applied through a rectifier resistor 62 to connect to anode 64 of 30 the first rectifier 49, and through a similar rectifier resistor 65 and connecting wire 66 to anode 67 of the second rectifier 51. A connection 68 is made from the point where the anode supply divides to a keying resistor 70. This keying resistor 70 is in series with the bias of an overbiased R. F. amplifier tube (not shown) contained in a radio transmitter assembly 71 comprising as an example, a master oscillator, buffer, and three stages of R. F. amplification, radiating from the 40 usual antenna system. Means for overbiasing such an amplifier tube are well known in the art.

45 The keying resistor 70 is placed in the circuit of the R. F. amplifier stage so that when current is passed through the resistor between connection 68 and ground 72, the voltage generated by this current will oppose the bias of the amplifier tube, thus reducing the bias and allowing the radio transmitter to operate. When no current is flowing through resistor 70, the bias on the 50 radio frequency amplifier blocks the transmitter and no signals will be radiated. The complete operation of this circuit will be explained separately.

55 In addition to applying certain signal variations to a radio transmitter through the circuits just described, I also prefer to transmit a synchronizing pulse. I, therefore, take energy from the twenty-cycle alternator combination 28-29 which is present in leads 30, and apply it to an 60 amplifier input circuit 73, to amplify the synchronizing pulses. The amplified pulses are passed through a synchronizing pulse connection 74 to the resistor 70 opposite the grounded end. The output of this amplifier passes through 65 resistor 70, and these pulses change the bias on the R. F. amplifier to cause the transmission of the horizontal synchronizing pulse.

70 Furthermore, in addition to the steady bias on the rectifier tubes 49 and 51 provided by biasing assemblies 56 and 57, I prefer to provide an additional varying bias, more particularly, a bias that will vary each time an individual line is scanned. This varying bias is provided by placing on the end of the rotor shaft 25 a cylinder 88 75 having five equal circumferential portions of

5 different light transmission values so that a slit 81 positioned outside of the transparent cylinder will receive five different light values from axially positioned exciter lamp 82. The light passing through the slit is directed on a photoelectric cell 83, the output of which is applied to a pair of grids 84 and 85, connected in parallel, of a pair of amplifying tubes 86 and 87. The outputs of tubes 86 and 87, which appear as voltage drops across their respective plate resistors 88 10 and 89, are applied to the grids of the rectifiers 49 and 51 in opposite polarity.

15 The photoelectric cell 83 is energized by a cell source 90 connected across a cell resistor 91, one end of which is connected to grid 84 of amplifier tube 86, the other end being connected to the cathode 92 of amplifier tube 87. Thus, the varying bias of the two rectifiers 49 and 51 will depend upon the value of the transparency presented to the photoelectric cell, the general action 20 being discussed later.

25 The operation of the dissector 4 in general, as far as the scanning is concerned, is unusual only in that each line is scanned five times. The picture currents produced by the scanning process are represented by the voltage drop across the output resistor 12 and these voltages after being amplified, are applied to the inputs of amplifiers 47 and 48, one of which is a single-stage, and the other a two-stage amplifier. The outputs of these amplifiers are fed to the grids of the two rectifier tubes 49 and 51. Rectifier 49 has a steady positive bias on its grid and rectifier 51 has a steady negative bias on its grid. With this arrangement, the signal applied to the rectifier grids comprises a series of picture impulses whose heights are proportional to the light intensity of the picture elements being scanned, but due to the fact that the signals applied to rectifier 51 pass through an even number of stages, the pulses applied to it are of opposite polarity to those applied to rectifier 49 which receives its signal through an odd number of stages. Therefore, a signal which decreases the instantaneous negative bias on the grid 55 for 45 rectifier 51, tending to make its breakdown voltage lower, will increase the instantaneous negative bias on grid 54 on rectifier tube 49 which has a steady positive bias, which tends to prevent it from breaking down. It is believed that 50 the following description will be simplified by reference to the passage of current through the rectifiers as "firing".

55 Since the anodes 64 and 67 of the grid-controlled arc rectifiers 49 and 51 are supplied with 55 alternating current from the two thousand-cycle generator, their breakdown is controlled by the grid voltage which is effective at the beginning of each positive half-cycle of the two thousand-cycle supply. By adjusting the resistors in 60 the respective biasing assemblies 56 and 57, the rectifiers can be given a steady bias such that neither tube will fire when the signals due to a picture being scanned are within a given range for values corresponding to a given range of 65 light intensity on elementary areas in the picture. When neither tube fires, the voltage drop across the keying resistor 70 is such that on the positive halves of the two thousand-cycle supply the voltage is sufficient to unblock the grid 70 of the radio frequency amplifier in the transmitter and cause signals to be transmitted by the antenna attached thereto.

If either rectifier tube 49 or 51 fires or if both rectifiers fire together, the voltage drop 75

across the keying resistor 70 is then not sufficient to unblock the R. F. amplifier and no radio signals are sent out. The reason for this is quite apparent because if both tubes are dark, no current will be taken by them and the maximum flow of current will be passed through the anode supply line and through resistor 70 to ground 72. If, however, either one of the tubes is passing current, current which flows through resistor 70 is used in one or both of the tubes and is therefore not available in resistor 70 to create a voltage sufficient to unblock the amplifier grid. It is, therefore, seen that the two rectifier tubes together can be controlled to operate the radio transmitter only when they receive signals corresponding to a given level or range of light intensities.

The manner in which these two rectifier tubes operate to control the radio transmitter and release energy therefrom only for picture elements which lie within a given range of light intensity can best be explained by reference to a specific numerical example, and reference will also be had to Figures 5 and 6, which show the grid voltage-firing voltage curves of the two rectifiers, plotted one above the other and to the same scale, Figure 5 representing tube 49 and Figure 6, tube 51.

Let us assume that the alternator voltage is two hundred volts peak at two thousand cycles. Since I prefer to design the alternator to supply a current having a waveform substantially flat-topped and substantially perpendicular sides as shown in Figure 3, there will be no operation of the rectifiers except under the condition of full two hundred volts applied anode voltage. For a full plate voltage of two hundred volts, the negative grid bias must be more than twenty-one volts to prevent the tube from firing. Continuing with the numerical example, let the steady battery bias on rectifier 49 supplied by bias assembly 56 and the drop across resistor 89 be +10 volts and the steady bias applied to rectifier tube 51 by means of the bias assembly 57 and the drop across resistor 88 be -53 volts. It will thus be seen that when no picture signal is supplied, rectifier 49, whose grid has a bias thirty-one volts more positive than the critical value of -21 volts required to stop the discharge, will fire on every positive pulse supplied by the alternator. On the other hand, rectifier tube 51 has a bias which is thirty-two volts more negative than that required to prevent discharge and, therefore, it remains inoperative as long as there is no picture signal.

As already explained, the picture signal is fed to the rectifier tubes through two separate amplifiers, one having an odd and the other an even number of stages. Therefore, a picture element which tends to increase the effective negative bias on tube 49 will decrease the effective negative bias on tube 51.

Let us assume that we are scanning a line of the picture, and we wish to send out signal pulses only for picture elements which will produce signal voltages between thirty-one and thirty-two volts. Referring to Figures 5 and 6, rectifier tube 49 has a steady bias on it of +10 volts and rectifier tube 51 has a steady bias of -53 volts. During any one scanning line the drops across resistors 89 and 88 remain constant.

Applying different values of signal voltages, we find the following:

(a) A signal of 31.1 volts makes the effective bias on rectifier tube 49, -21.1 volts, so that

this tube cannot fire. The same signal at the same time reduces the effective bias on rectifier tube 51 to -21.9 volts so that tube 51 is also inoperative. Under these conditions, the voltage drop across the keying resistor 70 is sufficient to unblock the R. F. amplifier and cause the radio transmitter to send out signal impulses.

(b) It can be shown similarly that tubes 49 and 51 will also be inoperative for signals lying between 31.1 and 31.9 volts and the radio transmitter will therefore operate in this range.

(c) If the picture signal drops below 31 volts, say to 30.9, the effective bias on tube 49 will be -20.9 volts and tube 49 will therefore fire and consequently, the radio transmitter will remain inoperative. At the same time, the bias on tube 51 will be -22.1 volts and it will not fire; but this is immaterial because radio transmission is prevented due to tube 49 firing.

(d) If the picture signal increases above 32 volts, say to 32.1 volts, the radio transmitter will be inoperative again because while rectifier tube 49 will then have a bias of 21.1 volts which will prevent its firing, tube 51 will fire due to its bias having been reduced to -20.9 volts which is less than the critical value. It is, therefore, seen that for given values of steady bias the rectifiers can be made to operate in such a way that the radio transmitter is energized only for picture elements having light intensities which lie within a given and predetermined range.

On succeeding scannings of the same line of the picture, following the procedure as outlined above, the voltage drops across resistors 89 and 88 are made to change to various values so that signals are sent out for picture elements of different levels of light intensities on each succeeding scanning. The voltage drops across these latter resistors are changed due to the action of the rotating film cylinder 80.

For example, to cause the transmitter to operate for picture elements delivering 10 to 11 volts to the rectifier grids, the transparent film for the scanning line in question is set to cause the photoelectric cell 83 to operate to pass sufficient current to make the sum of the drops across resistor 89 and the bias value placed on the grid 54 of the tube 49 by the biasing assembly 56, to be -11 volts. At the same time, the drop across resistor 88, together with the bias supplied by bias assembly 57 to tube 51 will become -32 volts; thus the range of light intensities which can cause the radio transmitter to operate is automatically set for each repeated scanning of the same scanning line by the drum carrying the transparent film, and its associated photoelectric cell, which, operating through amplifier tubes 84 and 85 fix the varying bias of the rectifiers.

It should be noted that the grid bias voltages controlled by the photoelectric cell 83 are applied to the rectifiers through separate amplifier tubes 86 and 87. The outputs of these tubes, which appear as voltage drops across their plate resistors 89 and 88, are applied to the grids of the rectifiers in opposite polarity. It should also be noted that the characteristic curves of the rectifiers are straight lines. While this linearity is a fortunate circumstance in that it makes for an easy adjustment of the two circuits, it is not necessary for the operation of the system as shown, as other adjustments would be readily apparent to those skilled in the art, to compensate for any curvature.

As indicated, in Figure 2, the transparencies on

the rotating drum are arranged in orderly manner so that the bias provided to the rectifiers 49 and 51 starts in at a low value for the first scanning of a line and ends at a high value at 5 the end of one revolution of the shaft, which is at the end of scanning of that one particular line.

The voltage generated by the photoelectric cell 83, when plotted on a time basis is shown in 10 Figure 7.

By proper selection of transparencies for the rotating drum 80 and by adjusting the steady bias assembly 56 and 57, it is possible to obtain any desired range of light values for each scanning 15 and it is quite obvious that certain shades may be accentuated if desired. In other words, the selection of the five different values need not necessarily differ by equal values and any arrangement may be made which will suit the subject matter best. However, for the five scannings 20 of the same line, we may adjust these values so that the radio transmitter is operating for example, as follows:

In scanning a given line:

- 25 First scanning—Transmit signals for picture elements producing 0 to 10 volts
- Second scanning—10 to 20 volts
- Third scanning—20 to 30 volts
- Fourth scanning—40 to 50 volts
- Fifth scanning—50 to 60 volts

It is obvious that the grouping of voltages referred to above is that which might be given when 35 an object was scanned five times, but it should be pointed out that my system as described is not limited to any particular number of scannings of a single line and that if a greater number of scannings is made, the range of voltage for the 40 picture elements on a single scanning will be less and for a lesser number of scannings the range will preferably be greater. It is possible, however, because of the extreme sensitivity of the arc-controlled rectifier tube to reduce the range 45 to a fraction of a volt where a single line is being scanned a large number of times in order to obtain extreme detail.

As explained above, a pulse amplifier is provided 50 which is connected to the scanning oscillator 19 and to the keying resistor 70 to send out a synchronizing pulse at the end of each traversal of a line. The polarity of the synchronizing pulse and the intensity are such as to completely unblock the radio frequency amplifier in the same 55 manner as the pulses produced by the two thousand-cycle generator, and to cause the radio transmitter to send out a synchronizing signal at the end of each traversal of the field by the scanning aperture. This signal is adjusted preferably to be 60 of a length corresponding to ten per cent of the period of scansion of one line, which for the present example would be ten per cent of .05 second, or .005 second. The synchronizing pulse is, therefore, ten times as long as any one of the two 65 thousand-cycle picture pulses sent out by the transmitter and can therefore be readily separated from these picture pulses at the receiving end by a simple resistance-capacity filter, as will be later described. It is also an advantage to 70 make the corners of the synchronizing pulses rounded to facilitate separation from the signal at the receiver and this may be done by control of the amplifier waveform as is well known in the art.

75 The description above given completes the cir-

cuits and operation thereof in the complete telephoto transmitter. I prefer, however, in order to check the operation of the transmitter to utilize a visual monitor assembly 95 for picking up the radio space current in a miniature receiver so that proper adjustment may be maintained on the transmitting device. This is in accordance with all modern practice and the general operation of the visual monitor will be similar to that of the receiver about to be described, with the exception that it may be possible, if desired, to utilize synchronizing pulses taken directly from the main transmitter.

At the receiving end, a preferred example of which is indicated by the diagram comprising 15 Figure 4, the output of a radio receiver 100 of ordinary design is in the form of pulses grouped in accordance with the picture signals. This form of output has been described fully in my copending application referred to above and is obtained 20 by the use of an arc-controlled rectifier tube similar to that used in the transmitter, but preferably having an anode excitation of around five thousand cycles, the grid being controlled by the 25 amplified and rectified radio signal. This particular type of receiver output is used in order that the signal-to-noise ratio may be low and that the signals be separated from the noise which would ordinarily accompany it, due to the sharp 30 selection of amplitude inherent in the operation of a grid-controlled rectifier. In other words, the output is composed of a series of uniform amplitude, five thousand-cycle waves, the grouping of the series corresponding to the value of the 35 picture impulses being transmitted.

This grouped signal is passed through an output resistor 101 and fed through a grid connection 102 to the control grid 102' of a visual monitor cathode ray tube 103 which preferably has a fluorescent screen having a considerable time lag 40 in order that a number of lines of the received image be visible at one time for visual monitoring purposes. The output voltage from output resistor 101 is also led through a receiver connection 104 to the control grid 104' of a receiver 45 cathode ray tube 105. This cathode ray tube preferably has an instantaneous screen and the light therefrom is focused on a moving film 106 or sensitized paper which after being exposed is passed into an automatic developing and fixing 50 bath 107 to emerge as the finished product.

Both cathode ray tubes are thus simultaneously energized. At the same time part of the output of the radio receiver is conducted through connection 108 to a synchronizing amplifier tube 109. 55 The picture pulses are prevented from operating or influencing this synchronizing amplifier by means of a low pass resistance-capacity wave filter comprising a condenser 110, and resistor 111, a series capacity 112 and a grid resistor 114, 60 which discriminates against rapid steep-sided picture pulses and passes the rounded synchronizing pulses. The synchronizing pulse then appears alone in the anode circuit 115 of the synchronizing amplifier and controls, as in the 65 transmitter, the output of a receiving lateral scanning oscillator 116, the output of which is passed through transformer 117, through leads 118 to the lateral scanning coil 118' of receiver cathode ray tube 105, and also to monitor tube 70 103 as indicated by a broken circuit Y—Y.

The multivibrator 119 is connected to produce a sub-harmonic of four cycles, which is fed to the grid 120 of a four-cycle amplifier tube 121, the output of which passes through a relay winding 75

122. This relay will, therefore, operate once for every five cycles produced by the twenty-cycle scanning generator 116. The relay operated by winding 122 has movable arms, one of which, selector arm 124, is connected in series with a three-step-by-step selector 125 operating exactly the same as that shown enclosed in the dotted line 23 of the transmitter drawing in Figure 2. The output of this step-by-step selector is applied to the vertical scanning coil 126 of the receiver cathode ray tube through a supply line 127 and also to monitor tube 103 as indicated by a broken circuit X—X. The other arm 127' normally closed, controls the current from a relay assembly source 129, which is the main supply for a series of locking relays which operate to change the effective resistance of a main cathode ray tube by a resistor 130. The drop across this resistor is applied to a beam bias grid 130' of the visual monitor 103 through lead 131 and to the beam bias grid 131' of the receiver cathode ray tube by lead 132.

In order to reproduce in the receiver tubes the various shades appearing in the transmitted picture, it is desirable to change the bias on the cathode ray receiving tubes to a different steady value for each repeated traversal of the same scanning line, and to do this in synchronism with the rotation of the transparencies which operate the rectifier bias supplies at the transmitter. This is readily done by relay arms 140, 141, 143 and 144 connected to short portions of the bias control resistor 130. The relays carrying the arms operate in sequence so that the bias of the cathode ray tubes starts at a high value when all the relay gaps are open. At the end of the first scansion of a given line at the transmitter a portion of the output of the lateral scanning oscillator 116 is picked up by a pulse winding 145 on transformer 117 and passed through a pulse amplifier 146. The amplified pulse is applied to the operating winding 147 of the first relay thus operating the relay, shorting out a portion of the resistor 130, and at the same time drawing down a locking arm 148. The bias is thus adjusted for the second scansion of the same line.

The actuation of the locking arm 148 closes a connection with a locking winding 149 of the first relay, the current passing also through an operating winding 150 of a first delay relay. Thus, the first bias relay is locked. In series parallel with winding 150 of the first delay relay is a condenser 151 which must charge before the first delay relay can close, and its value is made such that this relay does not close until after the pulse from the pulse amplifier has operated the first bias relay and then dropped to zero. After the pulse passes, and condenser 151 charges, winding 150 of the first delay relay becomes energized, closes a connection 150', shifting the output of the pulse amplifier 146 to winding 152 of the second bias relay. The pulse then operates bias arm 141 shorting another portion of resistor 130 and also operating locking arm 153, which latter arm closes the circuit to a delay winding 154 of a second delay relay.

The winding 154 is also shunted by a capacity 155, which delays the operation of this relay until the pulse has passed, whereupon the current passing through the winding 154 will operate transfer arm 155 and locking arm 156 which again transfers the output of the pulse amplifier to operating winding 157 of the third bias relay which in turn operates the bias arm 143 to short out still another portion of resistor 130, and oper-

ates locking arm 158 which closes the circuit and transfers current to the energizing winding 160 of the third delay relay, the latter winding being again shunted by a delay condenser 161. When the pulse dies out the third relay will operate on transfer arm 162 and locking arm 163 to energize the last bias relay winding 164 which in turn operates the bias arm 144 to short out the remainder of the resistor, and lock the bias relay. All of the delay relays have locking windings and remain closed during the progressive shorting of resistor 130.

At the end of five scannings of the same line at the transmitter, the receiver multivibrator actuates tube 121 and relay 122. This relay opens all the lock-up windings, releasing all of the relays and also operates the step-by-step selectors so that the spots of the cathode ray tubes are moved down ready for the next scanning line. The cycle is then repeated.

The four bias relays should be capable of closing in about .005 second. The three transfer relays, by having the condensers shunt them, are arranged to be time delayed by about .03 second after the operating voltage is applied. Relays for these speeds do not present any new problems as high speed relays operating much faster than this are available. However, I do not desire to limit myself to this particular method as many other means for effecting the desired bias changes for the cathode ray tubes will occur to those skilled in the art.

For example, a synchronous motor carrying a set of transparencies and a photoelectric cell such as that used at the transmitter might be substituted for the relays at the receiver or a series of arc-controlled rectifiers might be used. The apparatus described for this bias change is in itself no part of the instant invention and is simply used as an example of a means.

It can therefore be seen that the spot of the receiver cathode ray tube travels in synchronism with the scanning at the transmitter, that the transmitter scanning aperture traverses the same line several times, and that a pair of arc-rectifier tubes causes picture elements of different intensity ranges to be picked out, separated and transmitted during each repeated scansion. The signals thus produced key the radio transmitter so as to send out signals in the form of dots of uniform length, and shape, and a relatively longer dash is sent out at the end of each scansion for synchronizing the receiver.

At the receiving end the cathode ray tubes are provided with circuits which cause them to operate and scan their respective screens in synchronism with the dissector at the transmitter. Synchronism is effected by separating the synchronizing pulses from the picture pulses by means of a filter. Relay circuits operated by a twenty-cycle receiver oscillator change the bias on the cathode ray tubes to a suitable steady value corresponding to intensity of picture elements being transmitted, for each scansion. The receiver is also provided with a visual monitor having a time lag screen and a cathode ray tube arranged for automatic photographic recording.

The receiver is enabled to operate under conditions of relatively poor signal-to-noise ratio —2 or 3 to 1—because its output tube is a grid-controlled rectifier whose plate supply is fed by a five thousand-cycle a. c. source. The bias of this grid-controlled rectifier is adjusted so that it operates for the peak voltage of the signal, and

noise of less intensity than the signal does not appear in the picture.

I claim:

1. The combination with an electron image dissector of a telephoto transmitter comprising a picture field within said electron image dissector, means for scanning a portion of said field a plurality of times within said image disector to produce a picture signal before the remainder is scanned, a signal transmitter, and means for changing the response of said transmitter to said signal in accordance with different levels thereof at each successive scansion of said portion.
2. The combination with an electron image dissector of a telephoto transmitter comprising a picture field within said electron image dissector, means for scanning each line of said field a plurality of times to produce a picture signal before scanning the next line, a signal transmitter, and means for changing the response of said transmitter to said signal in accordance with different amplitude levels thereof at each successive scansion of said line.
3. The combination with an electron image disector of a telephoto transmitter comprising a picture field within said electron image disector, means for scanning a portion of said field a plurality of times to produce a picture signal before the remainder is scanned, a signal transmitter, and means for changing the response of said transmitter to said signal in accordance with different levels thereof at each successive scansion of said portion, means for scanning remaining portions in like manner, and means for transmitting a synchronizing signal between each successive scansion of all the portions.
4. The combination with an electron image disector of a telephoto transmitter comprising a picture field within said electron image disector, means for scanning each line of said field a plurality of times to produce a plurality of substantially identical successive trains of signals representing a single line before scanning the next line, a signal transmitter, means for selecting impulses within a different predetermined amplitude range from each of said identical trains, and means for keying the transmitter by the selected signals.
5. The combination with an electron image disector of a telephoto transmitter comprising a picture field within said electron image disector, means for scanning each line of said field a plurality of times to produce a plurality of substantially identical successive trains of signals representing a single line before scanning the next line, a signal transmitter, means for selecting impulses within a different predetermined amplitude range from each of said identical trains, means for grading the average levels of said ranges in accordance with the gradations of light and shade of said field if it is desired to transmit, and means for keying the transmitter by the selected signals.
6. The method of telephoto transmission which comprises scanning each line of a picture field a plurality of times to produce successive substantially identical trains of picture impulses before scanning the next line, selecting from each of

said trains impulses within a different predetermined amplitude range, transmitting the selected impulses, repeating the steps on succeeding lines, receiving said signals, creating a beam of electrons, modulating said beam by said signals, changing the average response of said beam by a different predetermined amount for each successive scansion of the same line, repeating the steps on succeeding lines, creating a visual indication of the strength of said beam, moving said beam in accordance with the scansion at the transmitter, and photographing said visual indication.

7. The method of telephoto transmission which comprises scanning each line of a picture field a plurality of times to produce successive substantially identical trains of picture impulses before scanning the next line, selecting from each of said trains impulses within a different predetermined amplitude range, transmitting the selected impulses, repeating the steps on succeeding lines, receiving said signals, creating a pair of electron beams, modulating both of said beams by said signals, changing the average response of said beams by a different predetermined amount for each successive scansion of the same line, repeating the steps on succeeding lines, creating a persistent visual indication of the strength of one of said beams creating a transient visual indication of the other of said beams, moving said beams in accordance with the scansion at the transmitter, photographing the transient visual indication and checking the transient indication by visual inspection of the persistent indication.

8. The method of telephoto transmission which comprises scanning each line of a picture field a plurality of times to produce successive substantially identical trains of picture impulses before scanning the next line, selecting from each of said trains impulses within a different predetermined amplitude range, transmitting the selected impulses, repeating the steps on succeeding lines, receiving said signals, creating a beam of electrons, modulating said beam by said signals, changing the average response of said beam by a different predetermined amount for each successive scansion of the same line, said amounts being changed to correspond to the amplitude range selection at the transmitter, repeating the steps on succeeding lines, creating a visual indication of the strength of said beam, and moving said beam in accordance with the scansion at the transmitter.

9. The combination with an electron image disector of a telephoto transmitter comprising a picture field within said electron image disector, means for scanning each line of said field a plurality of times to produce a plurality of trains of signals representing a single line before scanning the next line, a signal transmitter, means for selecting impulses within a predetermined amplitude range from each of said trains, means for cyclically varying the response of said signal transmitter to different impulse levels on successive scancions of each line, and means for producing constant value signals from said transmitter in response to said different impulse levels.

FRANK J. SOMERS.
